(57) **CLAIM**

The ornamental design for enclosure, as shown and described.

DESCRIPTION

FIG. 1 is a perspective view looking at the top, front left corner;

FIG. 2 is a top plan view;

FIG. 3 is a right side elevation view and the left side is an exact mirror image of the right side;

FIG. 4 is a front elevational view; and,

FIG. 5 is a rear elevational view.

The bottom is plain and unornamented. The broken lines are for illustrative purpose only and forms no part of the claimed design.
